ROTARY FILE

Roy Erickson, Deerfield, and Robert L. Kuenzel, Wilmette, Ill., assignors to Dial-A-Card, Inc., Northfield, Ill., a corporation of Illinois

Filed Sept. 8, 1965, Ser. No. 86,907

Term of patent 14 years

(Cl. D74—1)

Fig. 1

FIG. 1 is a front perspective view of a rotary file embodying our new design; and

FIG. 2 is a rear perspective view thereof.

The essential features of the design reside in the portions shown in solid lines.

We claim:

The ornamental design for a rotary file, as shown and described.
